ALEXANDER N. PIERMAN, OF NEWARK, AND NATHAN A. CURTISS, OF RAMSEY, NEW JERSEY, ASSIGNORS TO MILLER REESE HUTCHISON, OF NEW YORK, N. Y.

SILENCER FOR TELEPHONES AND THE LIKE.

Application filed January 22, 1924. Serial No. 687,693.

To all whom it may concern:

Be it known that we, ALEXANDER N. PIERMAN and NATHAN A. CURTISS, citizens of the United States, and residents, respectively, of Newark, in the county of Essex and State of New Jersey, and of Ramsey, in the county of Bergen and State of New Jersey, have invented certain new and useful Improvements in Silencers for Telephones and the like, of which the following is a specification.

Our invention is shown as embodied in a telephone silencer of a type set forth in the application of Miller Reese Hutchison, executed January 5th, 1924, and filed January 15 11, 1924. While the novel features herein disclosed are shown in combination with certain features of said Hutchison application and while said novel features are particularly adapted for use in such combination, 20 they are also useful in other relations.

Our device comprises a sound and draft transmitting conduit which has breather vents opening into a breather silencer which preferably surrounds and is mounted on said conduit. As in the Hutchison device, this conduit may be a sound collector in the form of a cylindrical tube of proper diameter for fitting the mouthpiece of a telephone transmitter and may be contoured at the outer 25 end to fit the mouth or both mouth and nose of the speaker. The purpose of the breather silencer is to permit through draft of air with as little resistance as possible consistently with the main purpose which is baffling, muffling and confusing sound waves so as to greatly decrease their intelligibility. Where the purpose is to permit breathing by the user, small volume and short length of the baffling labyrinth is also desirable to 30 minimize the amount of exhausted breath that must be churned back and forth in order to draw in a desired amount of fresh air.

In the primary form of the Hutchison silencer, these purposes are served by a construction wherein concentric cylinders are used as the partitions forming the passages between baffling points; the path for the breath and the sound waves is straight back 45 and forth parallel with the axis of the tubes; and the effective width, that is, the circumference of the annular passages must be greater than that of the collector tube which is six inches or more. In practice these primary limitations result in many other lim-

itations which it is the object of our invention to avoid.

The primary feature of our invention is that we form the partitions for the labyrinth edgewise about the cylinder instead of 60 parallel therewith. Preferably they are integral with the cylinder and are closed in circumferentially by a sheet metal cylinder accurately fitting the tops of the tubes. The edgewise arrangement gives complete flexibility for the designer. The partitions may be as near together or as far apart as desired. They may be annular or longitudinal or preferably both. Preferably the guiding partitions are in radial planes at right 70 angles to the axis of the main tube and the baffling partitions are lengthwise of the tube, openings through the partitions being arranged so that the waves travel circumferentially between baffling points. If desired, 75 however, and, particularly for other purposes, it is possible to arrange for the guiding partitions to be longitudinal and the baffling partitions circumferential.

In either case there is ample room to make 80 the partitions as thick as may be necessary to prevent vibration and conduction by the walls of the device. The cross-sectional area of the passages and also the ratio of their height to width may be widely varied without any of the above referred to limitations attendant upon the use of concentric cylinder partitions.

With radial partitions spaced only two to the inch, there is room on the telephone 90 muffler for at least five of the circumferential passages for the waves and if the muffler is three inches in diameter, the aggregate length of these passages will be, say, 40 95 inches as against the 12 inches described above as available in the Hutchison device. Moreover, the passages being curved, the waves tend to follow the outer side of the curve and this affords an effective friction surface which the straight moving waves are 100 continuously impinging. This is particularly effective in wearing out and destroying the high frequencies upon which the intelligibility of voice sounds depends.

The above efficiencies are such that we 105 find it is perfectly practicable to have two diametrically opposite sets of baffling partitions and corresponding outlets dividing the total available space into two entirely separate paths for the waves. The amount 110

of energy in each path is only half as much but the number of baffling points is the same. Moreover, the effective acoustic length between baffling points is approximately four 5 inches or the total length from the inlet to the outer air is eighteen inches or more. These lengths are of acoustic importance because it permits quarter waves of many of the more important frequencies of speech to 10 be contained within the space between baffling points, while half waves and even entire waves of the lower frequencies are contained within the total length of the device. Both of these features seem to be of advantage 15 as regards the effectiveness of reflections occurring at the baffling point and also as regards tendency to reduce vibration of the device or parts thereof such as can be communicated to the telephone transmitter 20 to repair purity of transmission therethrough.

Another important feature is that both 25 guiding partitions and baffling partitions being radial, it becomes practicable to die cast said partitions integral with the main tube and with the nosepiece, if the latter is used.

The above and other features of my invention may be readily understood from the following 30 description in connection with the accompanying drawings, in which—

Fig. 1 is a side elevation of the complete device, with the outer cylinder broken away to diametric section;

35 Fig. 2 is a rear end elevation;

Fig. 3 is a characteristic cross-section showing a modification.

In these drawings the conduit 1 for receiving the air pressures and sound waves 40 is a tube adapted to fit over the mouthpiece of a telephone transmitter. When used for this specific purpose, the tube may be contoured as at 2 and may be provided with a nose shield 3 to fit the face of the user; also 45 it may be secured to the telephone transmitter by an abutment flange 8 covered with cushioning material 9 against which the front edge of the telephone mouthpiece is held by forwardly directed springs 12 secured 50 at the rear end by screws 13, each spring and the screw held being preferably countersunk in a recess as shown.

The tube 1 is provided with a lateral vent 55 16 of ample outlet area for escape or inlet of the air in response to the varying pressures. Such vent also permits escape of the sound waves and the silencer for muffling these and, in the case of voice waves for rendering them unintelligible, comprises radial 60 partitions, including end walls 17, 18 and intermediate guiding partitions 19, 20, 21 and 22; which are preferably in parallel planes at right angles to the axis of the tube 1, and preferably are equally spaced.

65 The annular spaces between partitions

communicate through openings as 29, 30, 31 and 32 which are so arranged that the air draft and sound waves must traverse relatively long circular paths in the interspaces in order to escape through the successive 70 openings.

Preferably each annular space is baffled by a transverse or bulkhead partition and this may be accomplished for all of said spaces by a single longitudinal partition 40. 75 The partition affords impact surfaces which tend to baffle the sound waves but afford very little resistance to the air drafts which are air currents that flow around the curves at speeds much slower and for periods almost 80 incomparably longer than the air movements constituting the movement phases of the sound waves.

If desired, one or more of the baffling partitions may be arranged to constitute walls 85 of the openings through the guiding partitions, and as shown in Fig. 1, the area of the opening is preferably the same as the cross-sectional area of the annular spaces which are connected thereby.

The outer edges of the partitions are preferably formed as elements of a true cylinder so that the annular spaces, as also the openings between the partitions, can be closed in by cylindrical tube 50 which may 95 be applied by sliding it endwise over the partitions.

As indicated in Fig. 2, the air draft and remnants of sound if any, escaping from the outlet 32, traverse an approximately complete circle between partitions 22 and end-wall 18, escaping through outlet holes 56. These holes are preferably below tube 1, which tends to shield the remnant of sound from bystanders. A slot could be used, but 105 a plurality of distributed holes have a slightly better effect in confusing and muffling the sound.

While the above device could be constructed from tin or sheet lead, it is preferably made 110 of metal so heavy as not to vibrate materially either as a whole or in any of its parts, in response to any resonance effects that may be set up by the sound waves within the cavity. For telephone purposes this is important, because in spite of the use of springs 115 12 and cushion surface 9, vibrations such as are producible in thin spring metal walls, can be communicated to the microphone of the transmitter, thereby impairing the clearness of the transmission.

Such thick metal walls can be built up, 120 from heavy drawn tubing which serves for conduit 1, and enclosing cylinder 50, and from heavy rolled sheet brass which serves 125 for the partitions. For quantity production, however, this is expensive and as before explained, an important advantage of the radial partitions is that it permits of die casting 130 in one piece of the tube 1 with its inter-

nal abutment flange 9, its external partitions, and the vent slot 16.

Such casting requires only fitting of the cylinder 50 in order to complete the essential working parts of the device. If the external cylindrical contour of the die casting is not sufficiently accurate, or if a sand casting is used, it is a simple matter to machine the outer edges of the partitions to the true-cylinder contour.

As before explained, the above construction affords three or four feet of baffling passages and experience indicates that there is advantage in utilizing the space for two parallel passages in which the air and waves traverse semi-circles, instead of complete circles, between baffling points. This requires only the use of two transverse partitions as 50^a, 50^b, Fig. 3, with two corresponding sets of openings in the successive guide partitions, as 29^a, 29^b, for partition 19^a and 30^a, 30^b for the next partition; also two vent slots, as 16^a, 16^b, for tube 1. In this modification the two transverse partitions 50^a, 50^b may be in the vertical longitudinal plane of the device and the openings in the partitions may be recessed inward from the periphery along lines perpendicular to said partitions. This facilitates die casting since it permits of an exterior mold made in two sections, contoured so as to have proper draft lines of withdrawal from the complete casting, in directions perpendicular to the partitions.

As before noted, the simple construction problems presented in the foregoing remain the same for all thicknesses, spacings, lengths and cross-sectional areas for the walls, interspaces and openings. Hence the designer is free to vary these widely to get desired results in the telephone silencer or to adapt the silencer for air drafts other than the breath and sound waves of the voice.

The device may be made of other materials, as aluminum or aluminum alloy, hard rubber or even celluloid, although the latter is likely to be vibratory unless the walls are of ample thickness.

The device is shown as designed so as to slip over and off of the mouthpiece of a regular telephone transmitter, but, so far as concerns certain of the novel features, the rear end could be made a proper size and externally screw-threaded to screw into the front plate of the transmitter casing, as a substitute for the regular mouthpiece. Similarly, the device is shown as having the main conduit, 1, a true cylinder and the nosepiece joining the same by reentrant curves, but so far as concerns the novel features of the silencing labyrinth, said main conduit could be more or less conical or curved longitudinally and could be polygonal or even square or triangular in cross-section. Moreover, so far as concerns these

features, the vents from the main conduit to the silencing labyrinth need not discharge radially since the waves would be almost if not quite as well baffled if they entered the first annular passage in a direction parallel with the main conduit, as for instance through the front end radial flange.

It is to be noted that the labyrinths as designed are intended to baffle incoming drafts and sound waves as well as outgoing drafts and sound waves. Hence they may be designed to have the primary conduit associated with what are now the outlets, in which case the present outlets would serve as inlets and the present vent passages would become the outlets.

We claim:

1. A tubular conduit having a vent for air pressures and sound waves and, in receiving relation to the vent, silencer passages including radially extending partitions arranged edgewise on the exterior of said conduit, some of said partitions being circumferential and others longitudinal.

2. A tubular conduit having a vent for air pressures and sound waves and, in receiving relation to the vent, silencer passages including radially extending guiding partitions and baffling partitions arranged edgewise on the exterior of said conduit.

3. A tubular conduit having a vent for air pressures and sound waves and, in receiving relation to the vent, silencer passages including radially extending guiding partitions and baffling partitions arranged edgewise on the exterior of said conduit, the guiding partitions being parallel and having openings connecting the interspaces between them.

4. A tubular conduit having a vent for air pressures and sound waves and, in receiving relation to the vent, silencer passages including radially extending guiding partitions and baffling partitions arranged edgewise on the exterior of said conduit, the guiding partitions being parallel and having openings connecting the interspaces between them and the openings through the guiding partitions being adjacent the baffling partitions.

5. A tubular conduit having a vent for air pressures and sound waves and, in receiving relation to the vent, silencer passages including radially extending guiding partitions and baffling partitions arranged edgewise on the exterior of said conduit, said guiding partitions being in parallel planes at right angles to the axis of said conduit.

6. A silencer for telephone transmitters, including a tubular portion having breather vents between the mouth end and the transmitter end and radially extending partitions at the exterior of said tubular portion having their edges in contact therewith and means cooperating with the partitions to

provide silencing passages disposed so that the breath currents and the sound waves traverse to and fro paths, circumferentially of said tubular portion, alternately in opposite directions.

7. A silencer comprising a tubular portion having breather outlets and formed externally with radial partitions having outlet openings forming zig-zag passages with impingement surfaces at the ends of the passages, together with a surrounding tube fitting the peripheral edges of said partitions and forming peripheral walls of said passages.
- 10 8. The silencer specified by claim 7 with the further feature that the passages between the partitions communicate through open indentations in the peripheral edges of the partitions so that the surrounding tube also forms an outer wall for said indentations.
9. A silencer comprising a tubular portion adapted to fit over the mouthpiece of a telephone transmitter and formed in advance of said mouthpiece with breather outlets and 25 formed externally with edgewise partitions having outlet openings; and an exterior tube fitting over the outer edges of said partitions to form zig-zag passages having terminal impingement surfaces.
- 30 10. An integral casting comprising a tubular portion having one end adapted to fit

a telephone transmitter, said tubular portion being formed with breather outlets and formed externally with molded radial partitions, some circumferential and some transverse, and having cylindrical outer edges engaged and closed in by a surrounding cylinder, to form baffling passages for sound waves and for flow of air.

11. An integral casting comprising a tubular portion having one end adapted to fit over the mouthpiece of a telephone transmitter, said tubular portion being formed in advance of said mouthpiece with breather outlets and formed externally with radial 40 annular partitions forming communicating passages, having cylindrical outer edges adapted to be engaged and closed in by a surrounding cylinder.

12. A tubular conduit adapted to fit over and surround a telephone transmitter mouthpiece, in combination with a silencer passage for breathing purposes, comprising radially disposed guiding partitions and baffling partitions arranged edgewise on the 50 exterior of said conduit.

Signed at New York, in the county of New York and State of New York, this 21st day of January, A. D. 1924.

ALEXANDER N. PIERMAN
NATHAN A. CURTISS.
